UNITED STATES PATENT OFFICE

VINTON E. SISSON, OF CHICAGO, ILLINOIS, ASSIGNOR TO UNION METAL PRODUCTS COMPANY, OF CHICAGO, ILLINOIS, A CORPORATION OF DELAWARE

RAILWAY-CAR CONSTRUCTION

Application filed February 15, 1929. Serial No. 340,275.

This invention relates to railway cars and particularly to end walls for house cars provided with roofs, which end walls are made of metallic plates preferably reinforced with 5 integral corrugations or embossments.

This invention is an improvement over the construction shown in my Patent No. 1,071,813 of September 2, 1913, wherein the upper marginal portion of the metallic plate 10 is bent on diagonal lines to conform substantially to the slope of the roof to form a diagonal flange, which flange is secured to the opposite side plates of the car so that the flange performs the usual functions of the 15 end plate of the car.

The object of the invention is to strengthen this diagonal flange by re-flanging it into a depending flange and securing the depending flange to the opposite side plates of the 20 car. This depending flange preferably increases in width from the center of the car toward the opposite side plates.

In the drawings:

Fig. 1 shows a part of a railway car with 25 my invention applied thereon.

Fig. 2 is a plan view of Fig. 1 with the roof removed.

Fig. 3 is a section on line 3—3 of Fig. 1.

Figs. 4 and 5 show details of the flanged 30 plate.

Figs. 6, 7 and 8 show a modified construction.

Figs. 9 and 10 show another modified construction.

In the preferred form shown in Figs. 1 to 5 inclusive the upper margin of the end wall is bent on oppositely inclined diagonal lines 2 and 3 to form the lateral flange 4 which preferably increases in width from the middle of 40 the plate towards the opposite ends of the plate (or side plates of the car) which flange is provided with a re-flange 5 which preferably increases in depth from the middle of the plate towards the ends of the plate (or 45 side plates of the car.) This flange 5 may merge into the horizontal flange 6, as shown as Figs. 9 and 10. The diagonal flange is preferably secured to each side plate 8 by a clip angle 10 or any other convenient means and 50 the depending flange is also preferably se-

cured to each side plate by a clip 11 or any other convenient means. The lateral flange may be provided with a horizontal portion 6 to support the ridge pole 12 if one is used on the particular car. These end wall plates 55 may be reinforced with integral, preferably horizontal, embossments 13.

In the modification shown in Figs. 6, 7 and 8 the end wall comprises a plurality of plates secured together along vertical lines, preferably adjacent the middle of the end wall, which plates are preferably reinforced with vertical corrugations or embossments 20 having their upper ends adjacent the upper oblique flanges 21. These oblique flanges increase in width from the middle of the end wall to the sides thereof and the flange 22 also preferably increases in depth from the middle of the end wall to the sides thereof. The flange 21 of adjacent plates and also the 70 re-flange 22 of adjacent plates are preferably secured together by rivets 23 or 24 respectively.

This flange and re-flange construction can be made from a rectangular plate without 75 additional shearing of the plate.

The accompanying drawings illustrate the preferred form of the invention, though it is to be understood that the invention is not limited to the exact details of construction 80 shown and described, as it is obvious that various modifications thereof within the scope of the claims will occur to persons skilled in the art.

I claim:

1. In a railway car having oppositely disposed side plates, an end wall formed of metallic plates secured together along a vertical line adjacent the middle of the wall, said plates bent on oppositely inclined diagonal 90 lines to form flanges increasing in width toward said side plates, each of said flanges bent to form re-flanges.

2. In a railway car having oppositely disposed side plates, an end wall formed of metallic plates secured together along a vertical line adjacent the middle of the wall, said plates bent on oppositely inclined diagonal 95 lines to form flanges increasing in width toward said side plates to which they are se- 100

cured, each of said flanges bent to form re-flanges.

3. In a railway car having oppositely disposed side plates, an end wall formed of metallic plates secured together along a vertical line adjacent the middle of the wall, said plates bent on oppositely inclined diagonal lines to form flanges increasing in width toward said side plates, each of said flanges bent to form re-flanges increasing in depth toward said side plates to which they are secured.

4. In a railway car having oppositely disposed side plates, an end wall formed of metallic plates secured together along a vertical line adjacent the middle of the wall, said plates bent on oppositely inclined diagonal lines to form flanges increasing in width toward said side plates to which they are secured, each of said flanges bent to form re-flanges increasing in depth toward said side plates to which they are secured.

5. In a railway car having oppositely disposed side plates, an end wall formed of metallic plates secured together along a vertical line adjacent the middle of the wall, said plates bent on oppositely inclined diagonal lines to form flanges increasing in width toward said side plates, said flanges secured together adjacent the middle of the wall, each of said flanges bent to form re-flanges.

6. In a railway car having oppositely disposed side plates, an end wall formed of metallic plates secured together along a vertical line adjacent the middle of the wall, said plates bent on oppositely inclined diagonal lines to form flanges, each of said flanges bent to form re-flanges increasing in depth toward said side plates to which they are secured.

7. An end wall for a railway car formed of metallic plates secured together along a vertical line adjacent the middle of the wall, said plates bent on oppositely inclined diagonal lines to form flanges, each of said flanges bent to form re-flanges increasing in depth toward their outer ends.

8. An end wall for a railway car formed of metallic plates secured together along a vertical line adjacent the middle of the wall, said plates bent on oppositely inclined diagonal lines to form flanges increasing in width toward their outer ends, each of said flanges bent to form re-flanges.

9. An end wall for a railway car formed of metallic plates secured together along a vertical line adjacent the middle of the wall, said plates bent on oppositely inclined diagonal lines to form flanges increasing in width toward their outer ends, each of said flanges bent to form re-flanges increasing in depth toward their outer ends.

10. In a railway car having oppositely disposed side plates, an end wall formed of metallic plates secured together along a ver-

tical line adjacent the middle of the wall, said plates bent on oppositely inclined diagonal lines to form flanges increasing in width toward said side plates to which they are secured, each of said flanges bent to form re-flanges, said plates formed with substantially vertical embossments having their upper ends positioned adjacent said flange.

11. In a railway car having oppositely disposed side plates, a metallic plate end wall bent on oppositely inclined diagonal lines to form a flange increasing in width toward said side plates to which it is secured, said flange bent to form a re-flange.

12. In a railway car having oppositely disposed side plates, a metallic plate end wall bent on oppositely inclined diagonal lines to form a flange increasing in width toward said side plates to which it is secured, said flange bent to form a re-flange secured to said side plates.

13. In a railway car having oppositely disposed side plates, a metallic plate end wall bent on oppositely inclined diagonal lines to form a flange increasing in width toward said side plates to which it is secured, said flange bent to form a re-flange increasing in depth toward said side plates to which it is secured.

14. In a railway car having oppositely disposed side plates, a metallic plate end wall bent on oppositely inclined diagonal lines to form a flange secured to said side plates, said flange bent to form a re-flange secured to said side plates.

15. In a railway car having oppositely disposed side plates, a metallic plate end wall bent on oppositely inclined diagonal lines to form a flange secured to said side plates, said flange bent to form a re-flange increasing in depth toward said side plates to which it is secured.

16. A metallic plate end wall for a railway car bent on oppositely inclined diagonal lines to form a flange increasing in width toward its opposite ends, said flange bent to form a re-flange.

17. A metallic plate end wall for a railway car bent on oppositely inclined diagonal lines to form a flange increasing in width toward its opposite ends, said flange bent to form a re-flange increasing in depth toward its opposite ends.

18. A metallic plate end wall for a railway car bent on oppositely inclined diagonal lines to form a flange, said flange bent to form a re-flange increasing in depth toward its opposite ends.

19. A metallic plate end wall for a railway car bent on oppositely inclined diagonal lines to form a flange, said flange bent to form a re-flange.
